DINNERWARE WALL RACK

William Edward Moore, Chicago, Ill.

Application April 4, 1957, Serial No. 45,581

Term of patent 7 years

(Cl. D44—29)

Fig. 1

Fig. 2

A glass and dish are shown in broken lines for purposes of illustration.

I claim:

The ornamental design for a dinnerware wall rack, as shown and described.
